BOTTLE CAPPER

Charles M. Anderson, Kenosha, Wis.

Application August 15, 1932, Serial No. 628,921

5 Claims. (Cl. 226—92)

This invention relates to a bottle capper and more particularly to a hand-operated capping apparatus which is especially useful for capping milk bottles.

5 The primary object of the invention is to provide an improved hand-operated bottle capper which operates more accurately and efficiently than bottle cappers heretofore in use. Other specific objects and advantages will appear as 10 the specification proceeds.

The invention is illustrated, in its preferred embodiment, in the accompanying drawings in which—

Fig. 1 is a view in side elevation of apparatus 15 embodying my invention; Fig. 2, a broken sectional elevation taken as indicated at line 2 of Fig. 1, and at the line 2 of Fig. 3; Fig. 3, an enlarged transverse sectional view, the section being taken as indicated at line 3 of Fig. 2; Fig. 4, a 20 broken sectional view in elevation, in the nature of a developed view, the section being taken at the line 4 of Figs. 6 and 7; Fig. 5, a broken sectional elevation similar to that presented in Fig. 4, with the parts in the position as when applying 25 the cap to a bottle; Fig. 6, a bottom plan sectional view taken at the line 6 of Fig. 4; Fig. 7, a plan sectional view taken at the line 7 of Fig. 4, showing the cap-transfer member at its innermost position of movement; Fig. 8, a view similar to 30 Fig. 7, but showing the cap-transfer member at its outmost position; Fig. 9, a transverse sectional view, the section being taken as indicated at line 9 of Fig. 7; Fig. 10, a broken sectional view showing a modified form of plunger head; and Fig. 11, 35 a transverse sectional view, the section being taken as indicated at line 11 of Fig. 10.

In the illustration given, A indicates a hollow casing member; B, a plunger slidably mounted in casing A and provided with a handle B'; C, a cap magazine member; and D, cap-feeding mechanism for transferring caps from the magazine to the casing barrel.

The casing A may be of any suitable construction. It preferably provides in its upper portion 45 a smooth bore 10 for guiding the cap-plunger B. Below the bore 10 is an enlarged bore 11 adapted to receive a bottle cap 12 and to permit sliding movement of the plunger head 13. At its lower end, the casing is provided with a bell 14 and an 50 inner stop 15 adapted to rest upon the top of the bottle. In my improved construction, the portion of the casing barrel which surrounds the plunger head 13 when it is in its upper position, is left open at 16 and 17 so as to permit easy access to 55 the interior of the barrel. Heretofore it has been

customary to have this portion of the barrel closed or provided with a narrow slot or aperture, which while affording a view of the inner working parts, did not permit the operator to remove obstructions, such as deformed caps and the like, from the interior of the casing.

5 The plunger B may also be of any suitable construction. As illustrated, it comprises a tube 18, the upper end of which is imbedded within handle B' and the lower end of which is threadedly connected to head 13. The lower portion of the tube 18 is slotted at 19 to permit the plunger to ride past the cross-pin 20 upon which guide pin 21 is supported. A spring 22 extends around the pin 21 and seats against the handle portion of the 10 upper end of the tube. Rigidly secured to the tube 18 is a collar 23 which is adapted to strike the upper end of casing A and thus to serve as a stop for the plunger movement.

The magazine C may also be of any suitable 15 construction. In the illustration given, the cylindrical body 24 of the magazine is formed integral with casing A so that the two parts are separated by a common wall 25. The wall 25 is apertured 20 at 26 near the base of magazine C so as to provide communication between the bottom of magazine C and the cap barrel 11. The magazine may be provided with a shoulder 27 adapted to support the tube 28 which carries a supply of caps. If 25 desired, the magazine may be provided with a vertical aperture 29.

The cap feeding mechanism D may be of any suitable construction by which caps may be transferred from the magazine C through the aperture 26 into the barrel 11. I prefer to employ, however, the mechanism illustrated, in which a tubular member 30 is rotatably journaled in the lugs 31 and 32 which are formed integral with casing A. Preferably, ball bearings 33 are positioned on opposite sides of lug 32 to provide easy rotary 30 movement against the upward or downward thrust. At the upper end of the tubular member 30, as shown more clearly in Figs. 2 and 3, four ball bearings 34 are mounted within apertures 35 in the wall of the tube and are confined therein 35 by the tapered wall 36 of the adjustment cap 37. By means of the tapered walls 36, the balls 34 may be held firmly or loosely against the curved or twisted blade 38 of the actuating rod 39. The upper end of rod 39 is secured rigidly to an extension 40 which is formed integral with the collar 23. In my improved construction, I prefer to have only the end portion 41 of rod 39 curved or twisted so as to produce rotary movement of the tubular member 30 only when the rod 39 45

approaches the upper limit of its travel. Fixedly secured to the lower end of tubular member 30 is a feeder arm 42 which is equipped with a head 43. As shown more clearly in Figs. 6 and 9, the head 43 is provided on its lower side with a slot 44 which receives freely the outer end of arm 42. The upper portion of head 43 is provided on its sides with guide grooves 45 and on its top side with a central groove or recess 46.

10 In order to guide the head 43 accurately throughout the entire limit of its travel, I employ guide tracks 47^a and 47^b. As shown more clearly in the bottom plan view of Fig. 6, the outer track 47^a is a relatively long curved member extending from the casing A below the magazine C and to a point some distance beyond the magazine C. It is preferably a flat metal member which is secured by screws 48 to the magazine C and to a curved wall 49 which is formed integral with magazine C. The magazine C is also provided on its inner side with a curved wall 50 which is also formed integral with the magazine C. The inner track member 47^b is secured by screw 51 to the inner curved wall 50. As shown more clearly 25 in Figs. 7 and 9, the tracks 47^a and 47^b are provided on their inner sides with thin flange extensions 52 which enter the grooves 45 of the feeder head 43, thus supporting the head as it moves from a point some distance beyond the magazine C through the magazine and up to the casing A.

In my improved apparatus, the feeding mechanism, and particularly the relation of the curved end 41 of actuating rod 39 with the tubular member 30, is so adjusted as to feed the cap from the magazine to the barrel after the plunger has seated the cap and while it is being raised. For this purpose, the actuating rod 39 is practically straight throughout its length except at the curved end 41. With this construction, when the plunger approaches its top position, the curved end 41 engages the ball bearings and rotates the tubular member 30 so as to throw the feeding head 43 toward the cap barrel.

45 In order to prevent the cap from being retracted as the head 43 is withdrawn, I provide a stripper pin 53 which enters the recess 46 of the head 43 and permits the head to ride past it but which engages the cap after it has entered the barrel and prevents its withdrawal.

In the modified form illustrated in Figs. 10 and 11, the plunger 18 instead of being threaded at its lower end and provided with a separate head, is flared outwardly to provide a tubular enlarged 55 head 54. Such a head has been found to reduce the cost of manufacture while at the same time, affording a sturdier and more efficient construction because of the absence of threaded connections.

60 In the operation of the capper, assuming that a cap has already been fed to the barrel, the plunger is depressed so that the head strikes the cap and forces it to its seat on the bottle. During the initial downward movement, the twisted 65 end 41 of blade 39 causes the feeding arm 42 to be retracted to the position shown in Fig. 8. After seating the bottle cap, the force of the spring 22 forces the handle upwardly, at the same time raising by means of collar 23 and extension 40, the actuating blade 39. As the curved end 41 of blade 39 comes into contact with the ball bearings 34, the tubular member 30 is rotated so as to bring the feeder head 43 forward through the magazine C to the position shown in Figs. 6 and 7, thus 75 forcing one of the caps from the magazine through

the aperture 26 and into the barrel 11. As the plunger is then pressed downwardly, the cycle of operations just described is repeated.

5 In the apparatus as described, the feeding arm is maintained always in accurate feeding position by the guide tracks 47^a and 47^b while, at the same time, the feeding head is protected by the curved walls 49 and 50. The latter walls not only serve as a protection but also as a means for supporting the curved tracks.

10 The operation of the capper is rendered more efficient and placed under less strain by having the cap-feeding operation take place during the withdrawal or raising of the plunger mechanism rather than during the seating stroke, as cappers heretofore have been operated.

15 The foregoing detailed description has been given for clearness of understanding only, and no unnecessary limitations should be understood therefrom, but the appended claims should be 20 construed as broadly as permissible, in view of the prior art.

I claim:

25 1. A bottle capper comprising a casing affording a cap magazine and a cap channel with an intercommunicating aperture through which caps may pass into the channel, a curved track provided by an integral extension of said casing and aligned with said aperture, a plunger in said channel, a tubular member rotatably supported in vertical position by said casing and equipped with ball bearings, an actuating blade engaging said ball bearings and having its lower extremity curved, means associated with said plunger for raising and lowering said blade, and a feed arm 30 carried by said tubular member and engaging said curved track, said arm being adapted to feed caps from the magazine into the channel.

35 2. A bottle capper comprising a casing affording a cap magazine and a cap channel with an intercommunicating aperture therebetween through which caps may pass into the channel, a curved track supported by said casing and in substantially vertical alignment with said aperture, a plunger in said channel, a tubular member 40 rotatably supported in vertical position by said casing and equipped with ball bearings, an actuating blade engaging said ball bearings and having its lower extremity curved, means associated with said plunger for raising and lowering said blade, a feed head slidably supported by said track and adapted to feed caps from the magazine into the channel, and a feed arm carried by said tubular member and engaging said feed-head.

45 3. A bottle capper comprising a casing affording a cap magazine and a cap channel with an intercommunicating aperture therebetween through which caps may pass into the channel, a curved track supported in substantial alignment with 50 said aperture, a reciprocating member in said channel for pressing caps into bottles, a rotatable member supported in vertical position by said casing and equipped with ball bearings, an actuating blade engaging said ball bearings and having its lower extremity curved, means associated with said reciprocating member for raising and lowering said blade, a feed-head slidably carried by said track, and a feed arm secured to the lower end of said rotatable member and having its free end secured to said feed-head.

55 4. A bottle capper comprising a casing affording a cap magazine and a cap channel with an intercommunicating aperture therebetween through which caps may pass into the channel, a plunger in said channel having its lower end 60

outwardly flared, a tubular member rotatably supported in vertical position by said casing and provided with two pairs of spaced ball bearings, an actuating blade extending between said pairs of bearings and having its lower extremity curved, means associated with said plunger for raising and lowering said blade, and a feed arm carried by said tubular member and adapted to feed caps from the magazine into the channel.

10 5. A bottle capper comprising a casing affording a cap magazine and a cap channel with an intercommunicating aperture therebetween through which caps may pass into the channel,

a plunger in said channel, a feed arm adapted to feed caps from the magazine into the channel, a guide support maintaining said feed arm in alignment with said aperture, means for actuating said feed arm, said means comprising a tubular member rotatably supported in vertical position by said casing and provided interiorly with abutments, an actuating blade extending between said abutments and having its lower extremity curved, and means associated with said plunger 10 for raising and lowering said blade.

CHARLES M. ANDERSON.
